UNITED STATES PATENT OFFICE.

PAUL W. FENTON, OF NEW YORK, N. Y.

PRICE-EXHIBITING DEVICE.

Application filed April 8, 1926. Serial No. 100,488.

The invention relates to changeable signs designed, for example, as price indicating means, such as may be utilized in exhibiting the price of gasoline at a filling station.

5 It has for its object to provide a substantial though cheaply manufactured device of this character which shall be compact and afford ample variation in the particular indicia employed, for example, over the prevailing range of prices. A further object of the invention consists in providing means whereby a particular indicator member may quickly and readily be selected or changed. The invention has for a further object to 10 so construct the device that it shall not be of undue size and afford a package convenient for shipping; yet which when set up for use will provide indicating members of relatively large size. The invention contemplates, also, a construction of exhibiting device wherein the individual plates are not detachable and consequently not likely to become lost.

25 The nature of the invention, however, will best be understood when described in connection with the accompanying drawings, in which—

30 Fig. 1 is a front elevation of the improved exhibiting device with placards or price exhibiting plates folded within an enclosing casing or housing member.

Fig. 2 is an end view thereof.

35 Fig. 3 is a front elevation of said device shown suspended from a suitable bracket, and the plates or placards hanging down therefrom in position for exhibition.

40 Fig. 4 is a fragmentary transverse vertical section taken on the line 4—4, Fig. 3, and looking in the direction of the arrows.

45 Referring to the drawings, 10 designates a sheet metal housing member or casing open along an edge as, for example, an inverted U-shaped member; and to the back of which suitable eyes 11 or like members may be attached for suspending the housing, as from a suitable support or bracket 12, Fig. 2. Pivoted substantially midway of the ends of the housing and to the walls thereof near their edges, as at the pins or rivets 13 and 14, 50 are two sets of plates or placards 15 and 16 which bear upon their opposite faces the figures or other indicating marks it is desired to display. For example, the respective plates may bear consecutive numbers 55 so that by selecting the proper plate from each set and permitting the same to depend

from the housing, as hereinafter set forth, the desired price may be displayed.

To this end, the plates which are thus pivotally mounted in the housing may be 60 swung out or caused to drop under the influence of gravity, for example, downwardly about their respective pins 13 and 14 and assume a substantially vertical position as indicated in Fig. 3. Normally, this is prevented by a strap 17 for the set 15 and a strap 18 for the set 16 of the plates. These straps are U-shaped and are pivotally mounted over the respective ends of the housing as by being pivoted about pins or 70 rivets 19 and 20 respectively and secured to the said housing near the ends and back thereof. The said straps are designed to swing outwardly, as indicated in the dotted line position, Fig. 3, to release the respective 75 sets of plates normally held thereby, and thus enable the desired selection to be made. Thereupon, those remaining and not desired are returned within the housing by forcing the same upwardly and are then retained and 80 concealed therein by swinging the straps back into position over the ends of the housing and lower open portion. By this expedient, the plates not in use are thus normally concealed and protected with the 85 housing, while two or four juxtaposed plates may depend from between the walls of the housing and display the desired information as shown in Fig. 3.

It will be understood, of course, that other information or legends 90 may be displayed in connection therewith upon the outer faces of the housing, as indicated, being embossed thereon, cut therein or otherwise applied thereto. To afford the same price indication from both sides, 95 plates may be numbered from 0 to 9 on one side, forming the right hand digit; and numbered 1, 2 or 3 etc., on other side, forming the left hand digit, thereby obtaining the range desired. This will necessitate four 100 plates being swung into exhibiting position and render prices visible from two sides.

In order to maintain the exhibiting plates in a substantially vertical position and to prevent, also, the plates of one set from becoming mixed in with those of the other and adjacent set, suitable means are provided to limit the inward movement of the plates in a direction opposite to their normal swinging in movement. To this end, 110 channel-shaped guide arms 21, 22 are arranged to be pivoted on the respective pins

13 and 14 along the lower edges of the walls of the housing and substantially midway of the ends thereof. These arms are adapted, when the device is not in use, to be swung 5 upwardly to embrace the lower edges of the housing; as indicated in Fig. 1, but do not extend sufficiently outwardly toward the ends thereof to interfere with the operation of the straps. When the device is in use, 10 the said guide arms are designed to depend from the lower edges as shown in Fig. 3, in juxtaposed relation—the back of the one being adjacent the back of the other with their respective edges fitting over the cor- 15 responding side edges of the depending plates. The extent of movement of the said arms, moreover, is limited to the substantially vertical position indicated by cutting away the tops thereof an amount sufficient 20 only to allow of this movement—the arms then striking against the lower edges of the housing which act as a stop therefor, (see Fig. 4 of the drawings).

I claim:

- 25 1. A price exhibitor, comprising a housing open along an edge, marked plates pivotally secured within the housing and adapted to swing therefrom into an exhibiting position, and a strap member pivotally secured to the housing and adapted to embrace the open edge of the housing to hold concealed therein the remainder of the plates not desired for exhibition.
- 30 2. A price exhibitor, comprising a housing open along an edge, marked plates pivotally secured within the housing and adapted to swing therefrom into an exhibiting position, means to limit the extent of outward swing of the plates, and means pivotally secured to the housing to hold concealed therein the remainder of plates not desired for exhibition.
- 35 3. A price exhibitor, comprising a housing of an inverted U-shaped member, marked plates pivotally secured within the housing along the bottom edges of said U-shaped member and individually adapted to depend therefrom, and means pivotally secured to the housing to hold concealed therein the
- 40 45 50 remaining plates.
- 55 4. A price exhibitor, comprising a housing of an inverted U-shaped member, two sets of marked plates pivotally secured within the housing along the bottom edges of the U-shaped member substantially midway of its ends and adapted to swing down-

wardly therefrom, and a pair of straps pivotally secured to the top of the housing at its ends and adapted to swing over the lower edges of the housing to hold concealed therein the remaining plates of the respective sets of plates.

5. A price exhibitor, comprising a housing of an inverted U-shaped member, two sets of marked plates pivotally secured within the housing along the bottom edges of the U-shaped member substantially midway of its ends and adapted to swing downwardly therefrom, a pair of straps pivotally secured to the top of the housing at its ends and adapted to swing over the lower edges of the housing to hold concealed therein the remaining plates of the respective sets of plates, and means to prevent a depending plate from swinging beyond the vertical.

6. A price exhibitor, comprising a housing of an inverted U-shaped member, two sets of marked plates pivotally secured within the housing along the bottom edges of the U-shaped member substantially midway of its ends and adapted to swing downwardly therefrom, a pair of straps pivotally secured to the top of the housing to hold concealed therein the remaining plates of the respective sets of plates, and channel-shaped arms pivoted to the lower edges of the housing to depend therefrom and embrace the respective edges of two juxtaposed depending plates.

7. A price exhibitor, comprising a housing of an inverted U-shaped member, two sets of marked plates pivotally secured within the housing along the bottom edges of the U-shaped member substantially midway of its ends and adapted to swing downwardly therefrom, a pair of straps pivotally secured to the top of the housing to hold concealed therein the remaining plates of the respective sets of plates, and channel-shaped arms pivoted to the lower edges of the housing to depend therefrom and embrace the respective edges of the two juxtaposed depending plates, the bottom of the channel-shaped arms being cut away at the inner end sufficiently only to limit movement of the arms to a substantially vertical position, whereupon said bottom contacts with the lower edges of the housing member.

In testimony whereof I affix my signature.

PAUL W. FENTON.
